UNITED STATES PATENT OFFICE.

JOHN J. FISCHER, OF MARION, INDIANA, AND WARREN R. PAYNE, OF DENOYA,
OKLAHOMA.

ELECTRICAL INSULATOR.

Application filed January 19, 1926. Serial No. 82,310.

This invention relates to electrical insulators, and has for one of its objects the provision of a device of this character which shall be provided with an opening for the reception of the wire and slots to permit the wire to be inserted in and withdrawn from the opening, the arrangement of the slots with respect to each other and the opening being novel and such that, while the wire may be readily inserted in and withdrawn from the opening, it is positively held against accidental displacement therefrom.

With the foregoing and other objects in view, the invention consists of the construction, combination and arrangement of parts hereinafter fully described and claimed, and illustrated in the accompanying drawing, wherein:

Figure 1 is a view in side elevation of an electrical insulator embodying our invention,

Figure 2 is a similar view looking at the opposite side of the insulator,

Figure 3 is a similar view looking at the insulator from a third side thereof,

Figure 4 is a detail sectional view taken on the plane indicated by the line 4-4 of Figure 1, and

Figure 5 is an elevational view of a modified form of the insulator.

Corresponding and like parts are referred to in the following description, and designated in the several views of the accompanying drawing, by similar reference characters.

The insulator 1 may be made of glass, porcelain or other suitable material, and is provided in its inner end with a threaded socket 2 to permit of its application to a pin mounted on a cross arm or other support.

The insulator 1 is provided adjacent its outer end with an opening 3 which extends diametrically therethrough and is provided for the reception of the wire. A slot 4 extending axially of the insulator 1 and opening out

through opposite sides thereof, is arranged at right angles with respect to the opening 3, and extends from the outer end of the insulator to a point inwardly beyond the opening. Slots 5 arranged at opposite sides of the

slot 4 and communicating therewith, incline 50 inwardly and laterally in opposite directions from the opening 3. The slots 5 open out through opposite sides of the insulator 1, and their open ends are in alinement with the inner end of the slot 4.

The insulator shown in Figures 1-4 is especially adapted for outside use, while the insulator shown in Figure 5 is especially adapted for indoor use. This latter insulator is provided at its inner end with an attaching screw 6, and to permit the ready application of the screw the insulator is made of similar sections. The insulator sections 1^a and 1^b are preferably of semi-cylindrical formation, and are provided in their inner sides and adjacent their inner ends with recesses 7 for the reception of the head 8 of the screw 6. The screw head 8 is provided with small projections 9 which fit in corresponding indentations in the walls of the recesses 7 and prevent the insulator and screw from having relative axial movement. The insulator sections 1^a and 1^b are secured together by bolts 10, the heads and nuts of which are embedded in the sides of the sections.

The wire may be readily inserted in the opening 3 by first carrying it into the slot 4 until it contacts with the inner or bottom wall thereof, then turning it until it is in parallel relation to the slots 5, and by thence 80 moving it outwardly in the slots 5. As the slots 5 incline inwardly and laterally in opposite directions from the opening 3 and as they are in planes right angularly related to the plane of the slot 4, there is no possibility 85 of the wire accidentally leaving the opening 3.

It should be understood that the drawing is merely illustrative and does not pretend to give exact proportions. Furthermore, the said drawing is illustrative of a preferred construction, it being our expectation that various changes and modifications may be made without departing from the spirit and scope of the invention.

What is claimed is:

An insulator having a diametrical wire receiving opening, an axial slot arranged at

right angles to the opening and extending out through opposite sides of the insulator, said slot extending from the outer end of the insulator to a point inwardly beyond the

5 opening, and slots arranged at opposite sides of the first named slot and extending inwardly and laterally in opposite directions from

the ends of said opening to the inner ends of the slot.

In testimony whereof we affix our signatures.

JOHN J. FISCHER.
WARREN R. PAYNE.
